UNITED STATES PATENT OFFICE.

CLARENCE D. FULLER, OF UTICA, NEW YORK.

MUFFLER.

1,360,517.

Specification of Letters Patent. Patented Nov. 30, 1920.

Application filed September 30, 1919. Serial No. 327,375.

To all whom it may concern:

Be it known that I, CLARENCE D. FULLER, a citizen of the United States, residing at Utica, in the county of Oneida and State of New York, have invented or discovered certain new and useful Improvements in Mufflers, of which the following is a specification, reference being had therein to the accompanying drawings.

10 This invention has for its object to provide an improved muffler, for internal combustion engines, which although mainly of sheet metal sections which may be readily stamped out, is of such construction that the sheet metal baffle plates or disks will be so protected from the hot gases of the exhaust that they will not burn out. The improved muffler also comprises a regulator by means of which the muffler may be properly adjusted for the most efficient operation in connection with any engine to which it is to be applied, all as will hereinafter more fully appear.

In the accompanying drawings Figure 1 is a longitudinal section of the improved muffler. Fig. 2 is a cross section of the same on line 2—2, Fig. 1, showing the regulating device. Fig. 3 is a section on line 3—3, Fig. 1, and Fig. 4 is a detail view showing the 25 means for holding the regulator in a position of adjustment.

Referring to the drawings, 12 denotes the flanged inlet head at one end of the muffler, said head having an internally screw threaded boss 13 for the reception of a nut 14 by which the muffler may be connected with an exhaust pipe. At the opposite end of the muffler is a flanged outlet head 15 having a boss 16 at the outlet opening. The body of 30 the muffler, between the end heads 12 and 15, comprises several cup-shaped sections 17 preferably stamped from sheet steel, each of these sections affording a disk-like baffle plate 17^a having several openings 17^b. These 35 sections 17 are formed with shoulders 17^c afforded by the reduced parts 17^d fitting or telescoping within the ends of the adjacent sections and against which shoulders the adjacent section abut.

40 Near the inlet head 12 is a baffle protecting plate 18 having openings 18^a, a lateral flange 18^b and a peripheral flange 18^c between which latter and a peripheral flange 12^a on the end head 12 is interposed a sheet metal ring 19 which abuts against said flanges 18^c and 12^a and is entered by a lateral

flange 18^b on the plate 18 and a lateral flange 12^b on the head 12.

The improved muffler is also preferably provided near the exhaust head 15 with a second baffle protecting plate 20 formed like the protecting plate 18 in that it has openings 20^a, lateral flanges 20^b and a peripheral flange 20^c between which latter and said exhaust head 15 is interposed a second sheet metal ring 21 which abuts against the flange 20^c on the plate 20 and also against a peripheral flange 15^a of the exhaust head 15, said ring being entered by a lateral flange 20^b on the plate 20 and a lateral flange 15^b on 50 said exhaust head.

The several sections of the muffler are held together by longitudinal tie rods 22 passing through the several sections thereof and provided at their ends, outside of the 55 end heads, with nuts 23, three of these tie-rods preferably being provided.

The end heads 12 and 15 and the protecting plates 18 and 20 are preferably of malleable cast iron and the lateral flanges on said heads and plates are preferably slightly tapering so that when the muffler sections are drawn together by screwing up the nuts 23 on the rods 22 the joints between the parts will be as tight as possible. The openings 85 in the protecting plates 18 and 20 may be out of register with the openings in the baffle disks or plates 17^a, so as to increase the efficiency of the protecting plates, particularly the plate 18 against which the hot 90 exhaust gases first come, while the second protecting plate 20 coöperates with the first protecting plate in stiffening the muffler and preventing metallic resonance or "tinny" sounds such as would occur to a greater degree with a sheet metal muffler without these 95 stiffening and sound-deadening parts. These protecting plates also serve as baffle plates, as will be understood.

To adapt the same sized muffler for use in 100 connection with different sized engines a regulator is desirably provided. This regulator preferably consists of a rotatably mounted plate or disk 24 which may be pivotally mounted on the plate 20 and which has parts or arms 24^a by which the openings 20^b in said plate may be closed more or less by turning said plate or disk 24 slightly in its pivot 25. The regulator 24 is provided with a part or handle 24^a extending outward through the muffler casing and by which the said regulator may be adjusted, 110

when necessary. The nut 26 on the pivot 25 may be screwed up tight enough to retain the regulator in any position to which it may be adjusted, but it is preferred to provide the handle 24^a, which is somewhat elastic, with a down-turned lug or projection 24^b adapted to engage any one of a series of notches 20^a in the peripheral flange 20^c of a protecting plate 20, and thus positively retain the regulator in place.

Most of the baffle plates 17^a will preferably be provided with several openings 17^b say about one or one and a quarter inches in diameter for a muffler say about six and a half inches in diameter, while one of these baffle plates may have a single large opening 17^c which will serve to vary the path of the current of gases passing through the muffler.

From the foregoing it will be understood that the invention provides an efficient muffler of inexpensive construction which will last indefinitely and which may be adjusted or regulated as may be desired. The invention is, however, not to be understood as being limited to the details herein shown and described, as these may be varied widely, within the province of mechanical skill, without departing from the essence of the invention as defined in the claims hereunto appended.

Having thus described my invention I claim and desire to secure by Letters Patent:—

1. A muffler comprising a series of sheet-metal baffle plate sections fitting together and having openings, end heads of cast metal and a cast metal protecting plate interposed between the inlet end head and the sheet metal baffle plate sections, combined with tie rods passing through these parts and by which the muffler sections are held together.

2. A muffler comprising a series of sheet-metal baffle plate sections fitting together and having openings, end heads of cast metal, a cast metal protecting plate interposed between the inlet end head and the sheet metal baffle plate sections, and a second protecting plate near the exhaust head, combined with tie rods passing through these parts and by which the muffler sections are held together.

3. A muffler comprising a series of sheet-

metal baffle plate sections each having a reduced part to enter an adjoining section 55 and a peripheral shoulder against which an adjoining section abuts, said baffle plate sections having openings, cast metal end heads having peripheral and lateral flanges, cast metal protecting plates near each end 60 of the muffler, said plates having openings and peripheral and lateral flanges, and sheet metal rings between said end heads and said protecting plates, combined with tie rods 65 passing through these parts and by which the muffler sections are held together.

4. A muffler comprising a series of sheet-metal baffle plate sections each having a reduced part to enter an adjoining section and a peripheral shoulder against which an adjoining section abuts, several of said baffle plate sections having relatively small openings and one of said sections having a single large opening, cast metal end heads having peripheral and lateral flanges, cast metal 70 protecting plates near each end of the muffler, said plates having openings and peripheral and lateral flanges, and sheet metal rings between said end heads and said protecting plates, combined with tie rods 75 passing through these parts and by which the muffler sections are held together.

5. A muffler comprising cast metal end heads having peripheral and lateral flanges, cast metal protecting plates also having 85 peripheral and lateral flanges, sheet metal baffle plates between said cast metal protecting plates, said sheet metal baffle plates telescoping together, and sheet metal rings 90 fitted between the peripheral flanges of said heads and the peripheral flanges of said cast metal protecting plates, combined with tie rods 95 for holding the muffler sections together.

6. A muffler comprising end heads and 95 baffle parts having openings, combined with a pivoted regulator by which the openings on one of said baffle parts may be closed more or less when desired, said regulator having a handle part extending through 100 the casing of the muffler, said handle part having a lug or projection, and a notched part to be engaged by said lug.

In testimony whereof I affix my signature.

CLARENCE D. FULLER.
